[57] CLAIM

The ornamental design for an artificial fishing lure, as shown and described.

DESCRIPTION

FIG. 1 is a perspective view of an artificial fishing lure embodying my new design;

FIG. 2 is a side view thereof, it being understood that the side opposite to that shown in FIG. 2 is a mirror image thereof;

FIG. 3 is a top view thereof;

FIG. 4 is a bottom view thereof;

FIG. 5 is a side view thereof showing a second embodiment with the tail section removed, it being understood that the side opposite to that shown is a mirror image thereof;

FIG. 6 is a front view of FIG. 1; and,

FIG. 7 is a rear view thereof.
